US00D914935S

(12) **United States Design Patent** (10) **Patent No.:** **US D914,935 S**
(45) **Date of Patent:** **** Mar. 30, 2021**

(54) **EXPLOSION-PROOF LIGHT**

(71) Applicant: **Jinsheng Deng**, Dongguan (CN)
(72) Inventor: **Jinsheng Deng**, Dongguan (CN)
(73) Assignee: **DONGGUAN PAN AMERICAN ELECTRONICS CO., LTD**, Dongguan (CN)

(**) Term: **15 Years**

(21) Appl. No.: **29/643,682**

(22) Filed: **Apr. 10, 2018**

(51) LOC (13) Cl. **26-02**
(52) U.S. Cl. **D26/41**

CLAIM

The ornamental design for an explosion-proof light, as shown and described.

DESCRIPTION

FIG. 1 is a perspective view of an explosion-proof light showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate portions of the explosion-proof light that forms no part of the claimed design.
